UNITED STATES PATENT OFFICE.

HARRY F. HITNER, OF MOUNT VERNON, OHIO, ASSIGNOR TO PITTSBURGH PLATE GLASS COMPANY, OF PITTSBURGH, PENNSYLVANIA, A CORPORATION OF PENNSYLVANIA.

ELECTRIC-MOTOR-CONTROL APPARATUS.

1,164,719.

Specification of Letters Patent.

Patented Dec. 21, 1915.

Application filed August 18, 1911. Serial No. 644,725.

To all whom it may concern:

Be it known that I, HARRY F. HITNER, a citizen of the United States, residing at Mount Vernon, in the State of Ohio, have 5 invented certain new and useful Improvements in Electric-Motor-Control Apparatus, of which the following is a specification.

The invention relates to electric motor control apparatus particularly designed for 10 use in drawing the glass cylinders employed in the manufacture of window glass; and the invention has for its object: the provision of an improved automatic controlling device for regulating the speed of movement of 15 the drawing mechanism during the entire operation of drawing a glass cylinder. One embodiment of the invention is illustrated in the accompanying drawings, wherein

Figure 1 is a side elevation of the glass 20 drawing apparatus; Fig. 2 is a diagrammatic view showing the general arrangement of the apparatus and its wiring; Fig. 3 is a detail plan view of the two motors employed and the means for gearing them together; 25 Fig. 4 is a diagrammatic side elevation of the geared switch employed; Fig. 5 is a section on the line V—V of Fig. 4; and Fig. 6 is a side elevation of the switch plug employed.

As shown in Fig. 1, 1 is the bait having 30 the usual hollow handle through which air is supplied to the interior of the cylinder being drawn; 2 is the glass cylinder which has been drawn and cut off at its lower end; 35 3 is the drawing carriage, which carriage is guided in its vertical movement by means of the guides 4; 5 is the drawing cable attached at its upper end to the drum 6; and 7 and 8 are electric motors of different horse power 40 for operating the drum 6 to raise and lower the carriage 3 and the bait carried thereby.

The driving connections between the motors 7 and 8 and the drum 6 are shown in detail in Fig. 3. The shaft of the motor 7 is 45 provided with a gear 9 meshing with another gear 10, which gear 10 is mounted upon a shaft carrying a worm 11. This worm 11 meshes with the worm-wheel 12 mounted upon the shaft carrying the drum 6. The motor 8 has a driving connection 50 with the shaft of the motor 7 by means of the magnetic clutch 13, and the spur gears 14, 15 and 16, so that the motor 15 may be

made to drive the drum 6 through the shaft of the motor 7 and the train of gearing 9, 55 10, 11 and 12. Also mounted upon the shaft 17 of the drum 6 is a geared switch 18, the construction and operation of which will be hereinafter described.

The operation of the mechanism just described and shown in Figs. 1 and 3 is controlled by means of the apparatus shown diagrammatically in Fig. 2 and in order that the object of this arrangement may be apparent before a detail explanation is offered, 60 it may be stated that the construction and arrangement of the controlling apparatus is such that after the edge of the bait 1 has been brought into contact with the molten glass in the drawing receptacle and the 65 proper switch placed in operating position, the following series of movements in the bait are secured. Starting at the surface of the glass the bait moves upward very slowly, forming the portion of the cylinder between 70 the points *a* and *b*, such movement continuing at a uniform speed and the distance between the two points being about twenty 75 inches. The speed of draw is then automatically increased, and while the portion of the cylinder between the points *b* and *c* is being drawn the increase in speed is gradual and uniform, the distance between the points *b* and *c* being about eight inches. At this 80 point in the drawing a further increase in speed occurs and this speed is maintained during the drawing of the remainder of the cylinder between the points *c* and *d*, after 85 which the cylinder is cut off. The cylinder must be moved upward still farther after 90 the cutting-off operation in order to be in position to engage the take-down-apparatus, and the construction of the controlling mechanism is such that by a manual shift in the switch plug a still higher rate of speed 95 in the movement in the bait and cylinder is secured, so that the cylinder is very rapidly moved from the position at which it is cut off to the position at which it may be shifted by the take-down-apparatus. When the carriage 100 3 and bait 1 are to be run down to the glass again for another operation, the switch plug is merely reversed from its last position, so that the bait is moved down to its position of engagement with the glass at a maximum rate of speed. The arrangement of 105

controlling mechanism whereby the foregoing movements of the bait are secured will now be described.

Referring now to Fig. 2, the principal parts of the controlling mechanism may be enumerated as follows: A is a generator for supplying current to the motors 7 and 8, such generator being of relatively high voltage, say two hundred and twenty volts for the purpose of illustration; B is a second generator of relatively low voltage, say thirty volts; C and D are switch sockets adapted to receive the switch plug E to be later described; F and G are the armature and field respectively of the large motor 7; H and I are the armature and field respectively of the small motor 8; 18 is the geared switch, heretofore referred to, which switch operates to cut out certain resistance and thus increase the speed of draw during the drawing of that portion of the cylinder lying between the points b and c, in a manner to be hereinafter described; K is a self starter whereby the resistance in the large motor circuit is gradually cut out as such motor starts; L is a limit switch operated by the movement of the carriage for automatically breaking the motor circuit when the carriage reaches its extreme upper position; M is an electromagnetically operated switch for short circuiting the limit switch when the current to the motor is reversed to run the bait down to drawing position; and N is the winding of the magnetic clutch 13 (Fig. 3), which clutch serves to connect the shafts of the two motors at certain times.

The construction of the switch plug E will be seen from Fig. 6. From this figure it will be seen that the body of the plug is made of some non-conducting material, such as wood, such body portion being provided on its opposite side with the contact springs 19 and 20, preferably of copper. When this plug E is pushed into the socket C, the spring portions 19 and 20 contact with the metal portions 22 and 23 of the socket C. The end of the plug is also provided with a brass pin 24 extending clear through the body portion, the opposite ends thereof extending slightly past such body portion. It will be seen that when this plug is pushed into position, the ends of the brass pin 24 contact with contact strips 25 and 26 in the socket C, so that a connection is made between such strips. The socket D is precisely the same in its construction as the socket C.

The geared switch construction is shown in Figs. 4 and 5. As here shown, the shaft 17 of the drum 6 (Fig. 3) is provided with the metal disks 27 and 28 with an interposed fiber disk 29, the disk 27 being keyed to the shaft 17, and the disk 28 being loose upon such shaft and having secured at one side a spur gear 30 meshing with another gear 31

on a counter-shaft 32. The two disks 27 and 28 with the interposed fiber disk 29 constitutes a slip connection for driving the gear 30, such gear with the disk 28 being pressed to the right by means of the spring 33 interposed between the gear and a collar 34 secured to the shaft 17. The shaft 32 also carries a switch arm 35, the outer end of which is adapted to pass over a contact segment 36 during the first half of its travel, and over a series of contact buttons 37 during the latter portion of its travel, resistance coils 38 being interposed between the contact buttons 37, so that the resistance is cut out as the arm 35 moves to the left. The switch arm 35 is free to swing upon the shaft 32 between the stops 39 and 40 carried by the side of the gear 31. The switch arm 35 is also provided with a pair of spring arms 41 and 42 adapted to contact with the members 39 and 40, the purpose in using such springs being to secure a quick movement of the arm 35 from the last contact button 37 to the contact button 42, at which time a shift from one circuit to another is secured as herein-after described, and so avoid danger of arcing. The slip connection for driving the gear 30 permits the arm 35 to be arrested by the stop member 54 at its proper starting position without interfering with the driving mechanism which may rotate after the arm 35 is brought to its proper position. The purpose and function of this geared switch will be more readily understood from the following general statement of the operation of the apparatus, during which operation the geared switch comes into play.

Starting with the parts in the position shown in Fig. 2, and with the lower edge of the drawing bait 1 in engagement with the surface of the glass in the drawing receptacle, the operation is as follows: The plug E is first placed in the socket C. This connection causes current to flow through the armatures of both the large and the small motors. Connection is made to the two sides 22 and 23 of the plug C from the low voltage generator B by means of the wires 43 and 44, and the circuit from such plug C through the armature F of the large motor 7 is completed via the wire 45, wire 46, the resistance in the self starter, the wire 47, limit switch L, and wire 48. This motor 7 does not start however as the resistance in the self starter K is such that the current from the low voltage generator is not sufficient to operate the motor. The other circuit completed by the insertion of the plug E is the circuit operated by the high voltage generator A, and includes the wire 44, the wire 49, the wire 50, the contact strips 26 and 25 and the pin 24 in the plug E, the wire 51, the geared switch 18, the wire 52, the armature of the small motor 8, the winding N of the friction clutch 13, the field I of the small motor, and

the wire 53 returning to the negative side of the large generator A. The completion of this circuit causes the clutch 13 operated by the winding N to engage, so that power from the small motor is transmitted through the train of connections shown in Fig. 3 to the winding drum, and a very slow movement is imparted to the bait for the formation of the neck thereof. This starting movement is exceedingly slow, inasmuch as the current through the geared switch must at first pass through all of the resistance segments 38. During the period in which that portion of the cylinder neck between the points marked *a* and *b* is being drawn the switch arm 35 (Fig. 4) moves from the stop 54 to the first button 37, and during this movement over the segment 36, there is no change in the speed of draw. As the switch arm moves over the buttons 37 however, the resistance segments 38 are cut out one after the other, and the speed of draw is gradually increased, such change of speed occurring as that portion of the cylinder between the parts marked *b* and *c* (Fig. 1) is being drawn. When the switch arm 35 shifts from the last button 37 to the button 42, the circuit through the small motor H is broken and the current instead of passing through the wire 52 to such motor, passes through the wire 55, the wire 56, the solenoid winding 57 of the self starter, and the wire 58. This causes the arm 59 on the self starter to move over the various contacts 60, so that the resistance in the self starter is cut out, thus permitting the large motor 7 to start and take up the drawing operation where such drawing operation was concluded by the small motor 8, the clutch 13 of course having been disconnected when the circuit through the small motor armature and clutch winding was interrupted by the geared switch. The large motor operated by the current from the low voltage generator circuit causes a more rapid movement of the bait than that given by the small motor, so that during the drawing of the cylinder from the point marked *c* to the point marked *d* (Fig. 1), a more rapid movement of the bait is secured. When the cylinder reaches the length to which it is desired to draw it (the length between the points marked *a* and *d* in Fig. 1), the plug E is withdrawn from the socket C, thus cutting off the current to the motor and stopping the drawing operation. The cylinder is then severed at the bottom in the usual way, and may now be moved up rapidly to the position at which the take-down apparatus engages the bait. To accomplish this rapid upward movement, the plug E is placed in the socket D. It will be seen that this causes current from the high voltage generator to pass through the wire 45 to the large motor, and describing the circuit heretofore set forth, return to the socket D via the wire 48. At the same time current is supplied to the winding 57 of the self starter K, to secure the cutting out of the resistance in such self starter, such current being supplied from the large generator via the wire 44, wire 49, wire 61, contact strip 62, pin 24 in the plug E, contact strip 63, wire 64, and wire 56, the return circuit from the winding 57 being through the wires 53 and 58 as heretofore described. The application of the high voltage through the large motor 67 secures the rapid raising of the cylinder to its highest position.

When the bait and cylinder reach their highest positions, the current is automatically cut off by the limit switch L. This switch is provided with a stem 65 adapted to be engaged by the projection 66 on the carriage when the carriage reaches its highest position, so that at that time the circuit through the wire 47 is automatically broken, thus stopping the operation of the parts.

In order to secure the downward movement of the bait and its carriage, the plug E is merely withdrawn from the socket D and reversed in such socket, thus causing a reversal of the current through the motor 7, and a backward movement thereof. Inasmuch as the limit switch L is open at the time of this reversal, it is necessary to complete the circuit in some other way, and to this end the short circuit around this switch L comprising the wire 67, switch arm 68 and wire 69, is provided. The switch 68 is controlled by an electro-magnetic winding M. It will be seen that the winding M is not excited to secure the actuation of the arm 68 during the forward movement of the motor 7, as the wire 69 leading to the winding is connected to the return side of the motor circuit, and the wire 71 leading from the other end of the winding is also connected to the return wire of the generator A. When, however, the plug E is reversed, the current passes through the wire 48, the wire 69, the winding M and the wire 71, thus securing the closing of the switch arm 68, so that the limit switch L is short circuited, the current from the wire 47 passing to the wire 48 via the wire 72, switch arm 68, and wire 69. The circuit through the motor can therefore be completed before the downward movement of the carriage permits the limit switch L to close.

Having thus described my invention and illustrated its use, what I claim as new and desired to secure by Letters Patent is the following:

1. In combination, hoisting means comprising a pair of electric motors, means for supplying current to the motors, resistance means in the circuit of one motor, resistance means in the circuit of the other motor sufficient to render such motor inactive, and means operated by the movement of the active motor for automatically cutting out

the resistance in the circuit of the active motor as the movement progresses, and finally cutting off the current to the active motor and cutting down the resistance of the 5 inactive motor.

2. In combination, hoisting means comprising an electric motor, means for supplying current thereto, resistance means in the circuit, and means operated by the movement of the motor for automatically cutting out the resistance, such means comprising a rotary switch-arm provided with a spring, a projection adapted to engage the spring and carry the arm rotatively, a friction slip 10 means for moving the said projection, and a stop for the arm.

3. In combination, an electric motor, a generator for supplying current to the motor, a resistance in the motor circuit sufficient to render the motor inactive, electrically operable cut-out means for cutting out such resistance, a second motor operable from the said generator, resistance means in the circuit of the second motor, and means 20 operated by the movement of the second motor for automatically cutting out the resistance in the second motor circuit, then breaking such circuit and sending the current through the said cut-out means whereby the resistance in the first motor circuit is cut out and such first motor becomes operative.

4. In combination, an electric motor, a relatively low voltage generator for supplying current to the motor, a resistance in the motor circuit sufficient to render the motor inactive, electrically operable cut-out means for cutting out such resistance, a second motor, a relatively high voltage generator 30 for supplying current to operate said first motor, resistance means in the circuit of the second motor, means operated by the movement of the second motor for automatically cutting out the resistance in the second 40 motor circuit, then breaking such circuit and sending the current through the said cut-out means whereby the resistance in the first motor circuit is cut out and such first motor

is operated by current from the low voltage generator, and a switch whereby the low 50 voltage generator circuit may be interrupted and the high voltage generator current applied to the said first motor.

5. In combination, hoisting means comprising an electric motor, means for supplying current thereto, a moving part operated by the motor, a limit switch in the circuit, positive means operated by the movement of the said part for opening the limit switch when the said part reaches extreme of movement, a second switch and connections for short circuiting the limit switch, an electro-magnetic winding for operating the said second switch, and connections whereby the reversal of the motor circuit secures the closing of the second switch whereby the motor 60 may be operated when the limit switch is open.

6. In combination, an electric motor, a generator for supplying current to the 70 motor, a resistance in the motor circuit sufficient to render the motor inactive, electrically operable cut-out means for cutting out such resistance, a second motor, a clutch for securing the shafts of the two motors in 75 driving engagement, an electro-magnetic winding for operating the said clutch in the circuit of the second motor, resistance means also in the circuit of the second motor, and means operated by the movement of the 80 second motor for automatically cutting out the resistance in the second motor circuit, then breaking such circuit and thus permitting the release of the clutch between the two motor shafts, and then sending current 85 through the said cut-out means whereby the resistance in the first motor circuit is cut out and such first motor becomes operative.

In testimony whereof I have hereunto signed my name in the presence of the two 90 subscribed witnesses.
